Des. 203,660
Patented Feb. 8, 1966

203,660

AUTOMOBILE FLOOR MAT

William H. Terrell, Akron, Ohio, assignor to The Buxbaum Company, Canton, Ohio, a corporation of Ohio

Filed Apr. 26, 1965, Ser. No. 84,966

Term of patent 14 years

(Cl. D9—6)

FIG.1

FIG.2

FIG.3

FIG.4

FIG.5

FIG.6

FIG. 1 is a front view in perspective, showing an automobile floor mat embodying my new design;

FIG. 2 is a plan view of the mat shown in FIG. 1 and shown on an enlarged scale;

FIG. 3 is a front view in elevation of the mat;

FIG. 4 is a rear view in elevation of the mat;

FIG. 5 is a side view in elevation of the mat as viewed from the left hand side of FIG. 2; and

FIG. 6 is a side view in elevation of the mat as viewed from the right hand side of FIG. 2.

I claim:

The ornamental design for an automobile floor mat, as shown.
